UNITED STATES PATENT OFFICE.

CHARLES S. BATDORF, OF BROOKLYN, NEW YORK.

ROTARY MOTOR.

No. 849,099.

Specification of Letters Patent.

Patented April 2, 1907.

Application filed February 9, 1905. Serial No. 244,981.

To all whom it may concern:

Be it known that I, CHARLES S. BATDORF, a citizen of the United States, residing in Brooklyn, in the county of Kings and State of New York, have invented certain new and useful Improvements in Rotary Motors, of which the following is a specification.

The invention has reference to an organization of movable elements which are capable of furnishing power, and embodies an arrangement whereby any of the elements may be elected to control the medium by which others are operated, and each element may be so mounted that power can be derived from either.

It is a design of the invention to so relate the elements that at no point during the operation of either will they rest upon a dead-center, for while each element is susceptible to a dead-center of its own the organization will be such that a dead-center common to the mechanism as a whole will be effectively overcome.

It is also a design of the invention to so relate the elements that the expending or failing force of one element will be combined with the initial force of another, whereby the integrity of the energy of the mechanism will be maintained. In conjunction with this feature of the invention, it may be said that the construction and relation of the elements will be such that neither will be called upon to take up the load or the load of the throw of another during their travel and comprehends such a correlation of parts that the force directed against each element and the relative location of said elements with respect to the force thereto imparted will always be such that the force of throw of the elements will be balanced or equalized through their respective paths of movement.

It is one of the most important designs of this invention to so construct and arrange one of the elements, that it will operate as a valve, in true balance, having an angular movement substantially without friction relatively to the medium during its operation, whereby notwithstanding its intended location under the constant pressure of a medium it will not be affected by such pressure to the extent of operating thereagainst with resistive force. In other words, it is intended to employ one of the elements as a balanced valve and that such a structure shall operate in and under the constant pressure

of a medium and yet not be subjected to the resistance therefrom.

It is a further and important design of the invention to effect a complete cut-off and exhaust of the medium to each actuator during a period in the travel thereof when the same is approaching and has arrived at its dead-center and to maintain such a condition until said actuator has passed beyond its dead-center point.

It is a further and an important design of the invention to construct a casing for the elements and which embodies a chamber which is divided into a series of contiguously-arranged compartments by a wall or walls through openings in which and which serve as ports the pressure may pass from one compartment, serving as a pressure-compartment, to the other compartments containing the transmitting elements, whereby the force of a medium may be directly transferred or switched from one compartment to another without material loss of the efficiency of the force of said medium, which loss would be due to frictional resistance during the travel of the medium in instances where such medium is conducted through avenues of considerable length—such, for instance, as pipes. By such construction it will be noted that the only resistance or friction to which the medium in this case will be subjected will be that due to the passage through the ports aforementioned and which, as is obvious, will be infinitesimal, and it will be readily observed, therefore, that the maximum force of the medium will be maintained.

The principles herein related may be embodied into any suitable form of mechanism, and it matters not whether each or any of the elements shall be dependent upon a particular motion or direction of travel in order to perfect an operable mechanism, and therefore for the purpose of explanation and rendering the invention more intelligible such invention may be embodied to comprehend a motor mechanism in which some of the elements will be operative relatively to others for regulating and controlling the flow of the medium to others, whereby the others will operate to govern the flow regulation, as well as to impart the power to the working elements.

An embodiment of the invention is illustrated on the accompanying sheets of drawings, whereon—

Figure 1 illustrates an elevational section of a motor incorporating the principles of this invention. Fig. 2 illustrates a sectional view of the same on line X X of Fig. 1. 5 Fig. 3 illustrates a view similar to Fig. 1; and Fig. 4 shows another relative position of the parts, also illustrating diagrammatically some of the various lines of force from a point of power with respect to axis of movement of a member and the movement of another member; and Fig. 5 illustrates a form of mechanism defining an adjustment which may be employed in connection with one of the elements, whereby to compensate for the 10 wear between the elements.

In the several illustrations similar characters of reference apply to similar parts.

Assuming the invention to be embodied in the form illustrated, the elements referred to 20 may be operatively mounted in a suitable casing 6, embodying a chamber supported upon a base 7 and which may be divided into three contiguously-arranged intermittently chambers or compartments 8, 9, and 10, respectively, the chambers or compartments 8 and 9 being separated by a wall 11, while branches 12 and 13 thereof may so partially divide said chambers or compartments 8 and 9, respectively, from chamber or compartment 10 that openings or ports 14 and 15, respectively, may be created to give immediate communication between the chamber or compartment 10 and the chambers or compartments 8 and 9.

35 The walls 16 and 17, respectively, of the chambers 8 and 9 may be substantially circumferential and may serve as paths about which the actuators 18 and 19, respectively, may operate, such actuators in the present 40 instance being mounted for movement upon axes concentric with said walls 16 and 17. The means for mounting the actuators may of course be of the most effectual and consistent character for the purpose of best gaining 45 the results sought to be obtained—as, for instance, by providing and mounting shafts 20 and 21 in suitable bearings 22 and 23, the actuators 18 and 19 to be mounted in such a case on said shafts, and, if desired, said actuators 50 may be keyed to said shaft by keys 220 and 230, although, as is obvious, this is a matter of choice in practice.

To those portions 24 and 25 of the shafts 20 and 21 which extend from the bearings 26 55 and 27, may be connected elements of a suitable train of mechanism by which the elements of the mechanism may be operated and by which the actuators may receive a simultaneous and alternate motion through 60 similar but independent paths. One of such trains embodies gears 28 and 29, respectively, suitably connected to the shafts—as, for instance, by keys 280 and 290—which are intermeshed for a relatively reverse movement, whereby a uniform travel of the actu-

ators may be had, and if the actuators 18 and 19 should be rotatably mounted—for instance, as is shown in the drawings—and geared together by the gears 28 and 29 then said actuators will travel through substantially similar paths, but in opposite directions, as indicated, for instance, by the arrows 30 and 31, the movement of said actuators, however, being in unison. Each actuator will during its travel through its path give similar results; but the results of one actuator will alternate with the results of the other actuator, and in this way a desired movement is given to a third member, (designated in a general way by 32,) 70 which is constantly in intimate contact with the actuators and which may be termed a “balance-valve” for regulating the flow of the medium whereby to govern the operation of the actuators.

80 One of the notable characteristics to be mentioned in connection with an arrangement of this character for the actuators is that during the travel of each there will be such an equalization of weight that they will 85 be free from resistance other than that normal resistance due to frictional contact of the elements and the elements and their paths, this being a desideratum in mechanisms.

The member 32 may of course within the 90 purview of this invention be of any suitable construction, and according to the manner of operation of the actuators said member 32 may be also likewise mounted for operation and which in the present instance may have 95 an angular movement.

As applicable to the present arrangement, as shown, therefore, said member 32 may embody a body portion and an extended member 33, which may be supported in connection with a suitable bearing 34—such, for instance, as by mounting the same upon a pivot 35—although such a construction is not essential, as the same may be suitably fulcrumed. The extremities 36 and 37, respectively, of the member 32, together with a considerable length of the body of the same, will move during a certain period in the openings in the dividing-walls and which form the ports 14 and 15, the opening and closing of the ports in the present instance and as will be understood from the illustrations being preferably intermittently effected and may be accomplished by having the extremities 36 and 37 contacting with 110 abutments 360 and 370 on the casing. It will be seen that the member 32 will operate in the chamber-compartment 10, which will be a chest from which the source of power may be derived, and therefore will be the 115 instrumentality by which the power will be intermittently admitted to and cut off from the chambers or compartments 8 and 9. During the operation of this member 32 in the chamber or compartment 10 attention is 120

125 130

drawn to the fact that notwithstanding that the member is constantly under the pressure of the medium, as seen by arrow 320, there will be no resistance or friction between said member and the medium, which is desideratum, the only friction to which this member can be subjected being that of frictional contact between it and the actuators and at its bearing. Each of said chambers 8 and 9 will be provided with exhaust-ports 38 and 39, respectively, which issue into an exhaust 40, and for the sake of simplicity a feed-pipe may be screw-threaded into the head 42.

As has been before remarked, the elements adapted to serve as actuators will have alternate movements through similar paths, and therefore in the construction shown such actuators may so be mounted on independent dissident shafts that the major portion of each will be disposed on diametrically opposite sides of each shaft and in opposite directions—for instance, as seen in Fig. 1—whereby the element 32 will receive a motion to intermittently open and close said ports 14 and 15.

Entering into that phase of the invention which comprehends the equalization of the weight or force of the elements during their operation, attention is drawn to Fig. 4 of the drawings, where is illustrated diagrammatically the amount of leverage present with respect to one of the elements during a certain position of travel of said element plus the amount of force being received by another element, it being understood that the leverage is here calculated upon the basis of the element plus the expanding or failing power. Assuming, therefore, that the actuators are in the position shown in Fig. 4 and the line of force is such as is indicated by 42, the actuator 18 will commence to offer a leverage equal to that from points 43 and 44, and at this point the power which has been driven into chamber or compartment 9 shall have commenced to be fully expanded. For counterbalancing this condition the member 32 will have sufficiently opened the port 15 at this juncture so that the full initial force from the chamber or compartment 10 will be directed against the actuator 19, and thereby substantially counterbalance the failing power in the chamber or compartment 9 plus the leverage of the actuator 18. When the actuator 18 shall have traveled around to a point giving a line of force at 44 through the actuator 18 the actuator 19 occupies a correspondingly diametrically opposite position the tendency of the elements would be to rest on a dead-center; but at this point the port 14 being entirely closed and the exhaust-port 38 sufficiently open to exhaust the chamber or compartment 9, the power within the chamber or compartment 8 will undergo its most energetic expansion, thus compensating for the loss of force with respect to the other member,

and this condition is substantially maintained throughout correspondingly relative positions of travel of the elements, whereby the integrity of the invariable energy of the mechanism is maintained.

It will now be noted that the actuators may be so mounted relatively to each other that they will move in diametrically opposite paths, whereby the throw of each will be equalized, and therefore it will not be encumbered upon one to take up the burden of weight of the other.

To maintain a contact between the various elements and for compensating for such wear as may take place therebetween, it may be desirable to adjust one of the elements relatively to the others, and while this may be accomplished in any suitable manner, such adjustment in the present instance, seems more practical in connection with the member 32. Such adjustment, therefore, may be accomplished by partially separating the branches 36 and 39 of said member 32 by an elongated slit 45, which may be extended from the outer surface of the member 32 to an approximate point relative to bearing 34, and each wall 46 and 47, respectively, may then be notched out or depressed so as to form recesses, which in combination may produce a tapered wedge-like opening 48, into which may be placed a member 49, the contour of such member 49 being made to correspond with the contour of the recess 48. Such member 49 may be operated relatively to the member 32 in any suitable manner—such, for instance, as by providing the same with a threaded bore 50, into which may be placed a threaded tap 51, having, for instance, a squared head 52, and which, when actuated by a suitable implement, will force the member 49 either up or down, whereby to either separate the branches 43 and 44 of the member 32 or allow them to draw together, and in order to permanently maintain the member 32 in its adjusted position I may provide the members 36 and 37, respectively, with lugs 53 and 54, having elongated openings 55 and 56, through which to pass a bolt 57, having a nut 58 adjustable thereon, so that when the member 49 has effected a suitable separation of the members 43 and 44 or they have been suitably contracted, as the case may be, such members can be held in permanent position at will by said member 49 and said member 57.

It will be noted that this invention embodies the use of plurality of members, each interdependent upon the other for its movement and each of which may be located and movable about its own axis and that some of the elements may be interdependent upon the others for the regulation of the power of the medium by which the others are operated, it being here remarked that it matters not what character of medium be employed, as

this is a matter of choice, and that the various elements will be maintained in contact with each other.

It will be seen from the foregoing, that the invention comprehends an organization of movable elements operable through independent paths, but each of which elements is interdependent upon the other for its movement, and which are capable of producing power, and that such power derived from the mechanism is increased by the fact that the elements can be so arranged that there will be a minimum of friction. Indeed, the only friction present seems to be that due to the contact between the parts, and it will be also observed in this connection that the member which operates in and in the present instance operates as a balance-valve and which is constantly maintained under a given pressure of medium is so constructed that no resistance is present between the member and the medium during its movement therein.

It has been pointed out, and is an important feature of this invention, that the conditions are always such that each element when approaching and arriving at its individual dead-center will be assisted through that period and farther on until it has passed such a point where it would be possible of itself to become inoperative upon its dead-center, and, as has been stated, these members when at this point are not subject to pressure by the medium.

Should the invention be embodied in a form, such as is illustrated and described, it will be noted that the pivotal point of the bearing of the oscillating member will at all times assume the entire pressure of the medium, and the construction of this member will always be such that during the various shifts thereof, the medium may be displaced without offering any resistance to the member.

It is also to be particularly noted that the parts are so arranged, and the oscillating member so actuated that the pressure from the medium will, at all times, be separated from that portion of the operative members which during their travel, offers the greatest resistance due at leverage, and in this connection it is to be noted that it no time during the operation of the members, will either of them be subject to back pressure. It is believed that this is the first time that this has been accomplished in motor-work.

It will be further noted that the compartment containing the medium is in such intimate communication with and preferably directed above the other compartments that the force of the medium from the pressure-compartment is instantaneously transferred and imparted into the compartment containing the working members at the instance of movement of the balanced member, and therefore, as is obvious, that friction which is

due to the travel of the medium and which detracts from the force thereof is overcome, thereby increasing the efficiency of that force.

It is one of the notable features of this invention that the elements of the mechanism are not only few, but that they each accomplish a plurality of functions. For example, these elements, which in the present instance are termed the "actuators" and which may be rotatably mounted in two of the compartments of the chamber, will be effective during their rotation for not only operating another member, but also for automatically, and intermittently cutting off communication to the exhaust-ports, thus avoiding the necessity of additional means for the performance of such a function.

Having thus described this invention, I claim—

1. The combination with working members, two describing independent orbits and one being movable about a fixed fulcrum relative to the axes of the two working members and operated thereby by contacting therewith, and the contacting portions of the fulcrumed member operating in parallel paths.

2. The combination with a casing having chambers, of an element operable in each chamber, one of said elements being balanced upon a bearing, and effectual for controlling the flow of medium to the other elements.

3. The combination with a casing comprising a chamber which is divided into compartments, of an element operable in each compartment, one of said elements being balanced and having an angular motion, and which is effectual for controlling the flow of medium to the other elements.

4. The combination with a casing comprising a chamber which is divided into compartments, of an element operable in each compartment, one of said elements being balanced upon a bearing and effectual for controlling the flow of medium to the other elements.

5. The combination with a casing comprising a chamber, having compartments, a rotatably-mounted member in two of said compartments, and an integral pivoted member in contact with both and actuated by said rotatably-mounted elements.

6. The combination with a casing having three chambers, a rotatably-mounted member in two of said chambers and a member movable about a fixed fulcrum in another chamber and actuated by said rotatably-mounted elements, said member having its end portions in contact with each of said rotatably-mounted members at the same time.

7. The combination with a casing having chambers, a rotatably-mounted member in two of said chambers, means for effecting the simultaneous rotation in opposite directions

of said members and a member movable about a fixed fulcrum and actuated by said rotatably-mounted members, said member having its opposite extremities in contact with rotatably-mounted members.

8. The combination with a casing comprising a chamber having compartments, a rotatably-mounted member in two of said compartments, and an integral pivoted member actuated by said rotatably-mounted elements, said pivoted member having each end thereof in contact with said rotatably-mounted members.

9. The combination with a casing having a chamber which is divided into compartments, one serving as a pressure-compartment, a rotatably-mounted member in two of said compartments, and a pivoted member actuated by said rotatably-mounted elements, said pivoted member having two portions in contact with said rotatably-mounted members, and adapted to admit the pressure from the pressure-compartment to the compartments containing the rotatably-mounted members.

10. The combination with a casing having a chamber, which is divided into intercommunicating compartments, of an element operable in each compartment, two side by side, and one above the two, one of said elements being balanced and in contact with others effectual for controlling the flow of a medium to the compartments containing the other elements.

11. The combination with a casing having three chambers, of an element operable in each chamber, one of said elements being supported on a fixed fulcrum and having an angular movement relatively to the movements of the other elements, and which is effectual for controlling the flow of a medium against the other elements.

12. The combination with rotatably-mounted pistons and an integral member rocked thereby, said member being movable about a fulcrum fixed between the pistons and relatively to a casing in which the parts are located, and which is given an angular movement by the pistons.

13. The combination with a power-chamber, of a working member operable therein and which is so constructed and arranged as to operate in true balance in the medium, portions of such member contacting with the walls of said chamber, working members operating in chambers communicating with the power-chamber, and by which the first-mentioned member is actuated to intermittently control the medium from one to another of said chambers.

14. The combination with pivoted and angularly-movable means and rotatably-mounted means operating about dissident axes for actuating the angularly-movable means.

15. The combination with a casing having

a power-chamber, of a fixed fulcrumed working member operable therein, and which is so constructed and arranged as to operate in true balance in the medium, portions of such member being in constant contact with working members operating in chambers communicating with the power-chamber, and by which the first-mentioned member is actuated to intermittently control the medium from one to another of said chambers.

16. The combination with a casing having a power-compartment of a fixed fulcrumed working member operable therein and which is so constructed and arranged as to operate in true balance in the medium, portions of such member contacting with the walls of said compartment, working members operating in other compartments communicating with the power-compartment, through openings in the wall which form the compartments, and by which the first-mentioned member is actuated to intermittently control the medium from one to another of said chambers.

17. The combination with an integral fulcrumed angularly-movable and balanced member having opposed extremities, and a bearing, of members suitably actuated for alternately raising and lowering said extremities.

18. The combination with a chamber divided by walls into compartments and having openings leading therethrough from one to the other, of an angularly-movable member operating in one compartment, and adapted to intermittently open and close said openings, and members operating in the other compartments and for actuating said first-mentioned member.

19. The combination with a chamber, having compartments with ports leading from one to the other, a member operating in one compartment and the ends of which intermittently open and close each port, members operable in the other chambers for actuating the first-mentioned member, and with which the extremities of the first member are in contact in unison, and means to effect a simultaneous motion of the last-mentioned members.

20. In a motor, the combination with two revolving members which revolve about dissident axes, and whose path of movement is in opposite directions, and a member mounted in a bearing which is intermediate the revolving members, said member being actuated by the revolving members by having its extended portions in contact with the revolving members.

21. In a motor, the combination with two revolving members which revolve about dissident axes, and whose path of movement is through independent and opposite circuits, a member mounted in a bearing which is intermediate the revolving members, said mem-

ber being actuated by the revolving members by having its opposite portions in contact with the revolving members, and means for maintaining the portions in contact with the members.

22. In a motor, the combination with two revolving members which revolve about dissident axes, and whose path of movement is through independent and opposite circuits, a member mounted in a bearing which is intermediate the revolving members, said member being actuated by the revolving members, by having its oppositely-disposed portions in contact with the revolving members, and means for maintaining the elements relatively in contact.

23. In a motor, the combination with two revolving members which revolve about dissident axes, and whose path of movement is through independent and opposite circuits, a member mounted in a bearing and which is actuated by the revolving members, means for operating the revolving members independent of the other member, and means for maintaining contact between the members.

24. The combination with a chamber having compartments with ports leading from one to the other, of a member operating in one compartment and which is in true balance during operation, and which has an angular movement, and is adapted to intermittently open and close said ports, and members operating in the other compartments and which are adapted to actuate said first-mentioned member.

25. The combination with a casing having a chamber divided into a series of compartments, one of which is a power-compartment, a working member located therein and adapted for controlling the power to the other compartments, movably-mounted members in said compartments and adapted to operate the working member, said movably-mounted member operating in opposite directions, and said working member being in constant contact with both movably-mounted members at the same time.

26. The combination with a casing having a power-chamber, of a working member operable therein and which is so constructed and arranged as not to be affected by the resistance of the medium, working members operating the chambers communicating with the power-chamber, and by which the first-named member is actuated to give it an angular motion and to allow it to intermittently control the medium, said first-named member being in contact with both working members and said last-mentioned chambers being provided with exhaust-ports which are opened and closed by the working members.

27. The combination with a power-chamber, of a working member operable therein and which is so constructed and arranged as

to operate in true balance in the medium, portions of such member contacting with the walls of said chamber, working members operating in chambers communicating with the power-chamber, and by which the first-mentioned member is actuated to intermittently control the medium from one to another of said chambers, said members being in constant contact, and means for maintaining contact between the members.

28. In a motor, the combination with three working members, two of which revolve, and one of which is integral and pivoted and has an angular motion in coincidence with the revolutions of the members.

29. In a motor, the combination with two revolving members which revolve about dissident axes, and whose path of movement is in opposite directions, and a member having an angular movement, and operated by the revolving members.

30. In a motor, the combination with two revolving members which revolve about dissident axes, and whose path of movement is through independent and opposite circuits, and a member having its extremities in contact with both revolving members, and by which it is balanced.

31. In a motor, the combination with a casing which is divided into compartments, of two revolving members which revolve in two compartments and about dissident axes, and whose path of movement is in opposite directions, and a member mounted in another compartment, and which is intermediate of the revolving members, said member being actuated by the revolving members by having its extended portions in contact with the revolving members.

32. In a motor, the combination with a casing having a chamber which is divided into compartments into two of which two revolving members, which revolve about dissident axes are mounted, and whose path of movement is through independent and opposite circuits, a member mounted in a bearing in another compartment which is above the compartments for the revolving members, said member being actuated by the revolving members by having its opposite portions in contact with the revolving members, and means for maintaining the portions in contact with the members.

33. In a motor, the combination with a casing, divided into compartments, and in two of which are revolving members, which revolve about dissident axes, and whose path of movement is through independent and opposite circuits, a member mounted in another compartment and in a bearing which is intermediate of the revolving members, said member being actuated by the revolving members, by having its oppositely-disposed portions in contact with the revolving mem-

- bers, and means for maintaining the elements relatively in contact.
34. In a motor, the combination with a casing which is divided into compartments, 5 two revolving members operating in two of the compartments and about dissident axes, and whose path of movement is through independent and opposite circuits, a member mounted in another compartment and which is actuated by the revolving members, means for operating the revolving members in unison, and means for maintaining contact between the members.
35. In a motor the combination with two 15 revolving members, means for revolving the same in opposite directions, and an intermediate angularly-movable working member driven intermittently through independent paths, and a bearing for the intermediate 20 member.
36. In a motor, the combination with working members, means for operating the same in opposite directions, and an intermediate angularly-movable member driven intermittently through independent paths, and a bearing for said intermediate member.
37. In a motor, the combination with a 25 casing having a chamber which is divided into three compartments, with ports leading from one to another, of a member operating in one chamber to open and close said ports, and members operating in contact with said member, for causing an intermittent movement of the member.
38. In a motor, the combination with a 30 casing having chambers and ports leading from one to another, of a fixed fulcrumed member operating in one chamber to open and close said ports intermittently, and means to shift the member to its open and closed positions.
39. In a motor, the combination with a 35 casing having chambers and ports leading from one to another, of a pivoted member having an angular motion and working in one of said chambers and adapted to intermittently open and close said ports, means actuating in said other chambers and which operate the working member, and means for 40 adjusting said member relatively to the actuating means.
40. The combination with three members in intimate and continual contact, one of which is supported on a fixed fulcrum and 45 has an angular motion and transmits power to the others, and independent means for transmitting motion from one to the other.
41. In a motor, the combination with two 50 revolving members and a fixed fulcrum member which is given an angular motion by the revolutions of the revolving members.
42. In a motor, the combination with two 55 revolving members revolving in opposite directions, but in similar paths, and a fixed fulcrum member in intimate contact therewith, and which is given an angular movement thereby.
43. In a motor, the combination with a 60 casing having a chamber which is divided into compartments, two rotating and one oscillating member in said compartments 70 said members being in close contact with each other and with the walls of the compartments.
44. In a motor, the combination with a 75 casing having chambers, two revolving and one oscillating pivoted member, said members being in constant contact with each other and the walls of the chambers, and means for operating some of the members in 80 unison.
45. In a motor, the combination with two 85 revolving disks rotating irregularly with respect to their centers of a pivoted member actuated thereby by having its ends bearing on said disks, said disks and member being constantly in contact, and said member being given an angular movement by the disks.
46. In a motor, the combination with two 90 revolving irregular-conformed members, operating irregularly with respect to their centers, of a member rocked thereby, and which is pivoted above and between the two, by having its ends in contact with the irregular members, means for maintaining the contact, and means for operating the revolving 95 members in opposite and similar paths.
47. In a combination of the class specified, a casing having a medium-containing compartment having ports for supplying a plurality of compartments, of movable parts in 100 said compartments, one of said movable parts, being supported on a fixed fulcrum and operated by the others for intermittently controlling the medium from the one to the 105 other chambers.
48. In a device of the character specified, the combination with an angularly-movable member mounted upon a bearing and having a to-and-fro movement in two directions, 110 said bearing assuming the pressure of the medium directed against the member, of members rotatably mounted and which lightly contact with the movable ends of 115 said member for operating the same intermittently.
49. The combination with a fixed fulcrum angularly-movable member, and members operating in dissident paths for effecting such 120 movement.
50. The combination with a member mounted upon a bearing and having an angular movement, a bearing therefor and which assumes the pressure of a medium directed against the member, of members operable for lightly contacting with and operating said member. 125
51. The combination with a fixed fulcrum angularly-movable member, adapted to open and close the ports of an engine, of members 130

traveling through dissident paths and in unison for effecting an intermittent movement of the member.

52. The combination with a pressure-chamber, of a pressure-controller mounted for angular movement therein, and a plurality of members operating in chambers communicating with the pressure-chamber, and adapted to operate the pressure-controller, said pressure-controller being adapted to divide the pressure from that portion of the members which offer the greatest leverage.

53. The combination of three elements, each interdependent upon the other for movement, and one being integral and supported about a fixed fulcrum and traveling about an axis eccentric to the axes to the others.

54. In a motor, the combination with a pivoted member, and two rotating bodies mounted eccentrically of common centers dissidently disposed.

55. The combination with a casing having chambers, of three elements operable therein, one of said elements having a fixed fulcrum and an angular movement which is given by the movement of the other elements and which element is effectual to control the flow of a medium to the chambers containing said elements.

56. The combination with two rotating pistons to an oscillating piston operated thereby, said oscillating piston being movable about a fulcrum fixed relatively to a casing in which the parts are located and which is given an angular movement by the rotating pistons.

57. The combination with two irregularly-formed rotatably-mounted pistons of an angular, movable piston operated thereby by being in close contact therewith, said movable piston being movable about a fulcrum fixed relatively to a casing in which all the members are located.

58. The combination with irregularly-formed movable members, and an angularly-movable member operated thereby and upon their faces, by being in positive contact therewith, said member being rocked upon a fulcrum fixed relatively to a casing in which all of the members operate and between the pistons.

59. The combination with revolving members, each so located that the throw of one will be equalized by the throw of the other, and an intermediate integral and pivoted angularly-movable member actuated by the revolving members.

60. In a device of the character specified, the combination with rotating bodies, of a fulcrumed balanced valve operated thereby for controlling a medium to the bodies, said valve operating to throw the medium to the outer side of the bodies.

61. The combination with revolving bodies, movable about dissident axes, and which are eccentrically mounted thereupon, and a bal-

anced and fixedly-fulcrumed member to which angular throw is imparted by the diversified movements of the revolving bodies.

62. The combination with two shafts located side by side of rotating bodies mounted on said shafts and operating in opposite directions, means for operating the bodies and a pivoted member angularly operated by said bodies.

63. The combination with chambers, of two shafts located therein, and side by side, and operating in opposite directions, means for operating the bodies and a balanced and fulcrumed member angularly operated by said bodies, and which is in intimate contact therewith.

64. The combination with a casing having chambers, of oppositely-rotating members in two of said chambers, and a pivoted member actuated by contact with the peripheries of said rotatably-mounted members.

65. In a motor, the combination with a pivoted member, two rotating bodies mounted eccentrically of common centers dissidently disposed, and a casing.

66. In a motor, the combination with a casing having intercommunicating compartments provided with ports leading from one to the other, one of said compartments receiving the constant pressure of a medium, a member balanced therein and having an angular motion for controlling the pressure from one to the other, and means to operate the member.

67. In a motor, the combination with chambers for receiving working members, one of which chambers serves as a pressure-chest for a medium, and which communicates with the others through openings formed in the walls on opposite sides of a wall between the chambers and a balanced fulcrumed valve operating in the openings for regulating the flow of the medium.

68. The combination with a casing having chambers, of an element operable in each chamber, one of said elements being balanced in and having an angular motion in one of the chambers, and effectual for controlling the flow of medium from one to the other of said chambers.

69. The combination with a casing having a chamber, which is divided into compartments of oppositely-rotating members in two of said compartments, and a pivoted member actuated by contact with the peripheries of said rotatably-mounted members.

70. The combination with a power-chamber, of a fixed fulcrumed working member operable therein and which is so constructed and arranged as to operate in true balance in and under the pressure of the medium, portions of such member contacting with abutments on the walls of said chamber, working members operating in chambers communicating with the power-chamber, and by

which the first-mentioned member is actuated to intermittently control the medium from one to another of said chambers.

71. The combination with a power-chamber, of a fixed fulcrumed working member operable therein and which is so constructed and arranged as to operate in true balance in the medium, portions of such members contacting with abutments on the walls of said chamber, working members operating in chambers communicating with the power-chamber, and by which the first-mentioned member is actuated to intermittently control the medium from one to another of said chambers, and means for creating contact between the members.

72. The combination with a power-chamber, of a fixed fulcrumed working member operable therein and which is so constructed and arranged as to operate in true balance in the medium, portions of such member contacting with the walls of said chamber, working members operating in chambers communicating with the power-chamber, and by the first-mentioned member is actuated to intermittently control the medium from one to another of said chambers, means for adjusting one of the members relatively to the others, and means for causing a relative operation of some of the members.

73. The combination with a casing having a series of chambers therein, one of which is a power-chamber, an angularly-working member located therein and adapted for controlling the power to the other chambers, said member working under the pressure of the medium, movably-mounted members in said chambers and adapted to operate the working member, said movably-mounted members operating in opposite directions.

74. The combination with a power-chamber, of a working member operable therein and which is so constructed and arranged as to operate in true balance in and under the pressure of the medium, portions of such member contacting with abutments on the walls of said chamber, working members operating in chambers communicating with the power-chamber, and by which the first-mentioned member is actuated to control the medium from one to another of said chambers.

75. The combination with a power-chamber, of a working member operable therein and which is so constructed and arranged as to operate in true balance in the medium portions of such members contacting with abutments on the walls of said chamber, working members operating in chambers communicating with the power-chamber, and by which the first-mentioned member is actuated to control the medium from one to another of said chambers, and means for creating contact between the members.

76. The combination with a power-chamber, of a working member operable therein

and which is so constructed and arranged as to operate in true balance in the medium, portions of such member contacting with the walls of said chamber, working members operating in chambers communicating with the power-chamber, and by the first-mentioned member is actuated to control the medium from one to another of said chambers, means for adjusting one of the members relatively to the others, and means for causing a relative operation of some of the members.

77. The combination with a casing having chambers of an element operable in each chamber, one of said elements being fixedly fulcrumed and effectual for controlling the flow of a medium to the chambers containing the other elements, the mounting of the said elements being such as to avoid pressure of the medium except on one side thereof.

78. The combination with a casing having chambers, of an element operable in each chamber, one of said elements being fixedly fulcrumed and having an angular movement, and which is effectual for controlling the flow of a medium against a plurality of elements, said member being under the constant pressure of the medium.

79. The combination with two members rotating in independent orbits of means operated thereby, said means being pivoted at a fixed point relatively between the axes of the rotating members.

80. In a motor, the combination with three working members two of which revolve, and one of which is integral and fulcrumed and has an angular movement in coincidence with the revolutions of the members, and means operatively connecting the two members.

81. In a motor the combination with two revolving members which revolve about dissident axis, and whose path of movement is in opposite directions, a member fixedly fulcrumed given an angular movement thereby, and gears connecting the members.

82. In a motor, the combination with two revolving members which revolve about dissident axis, and whose path of movement is through independent and opposite circuits, a fixedly-fulcrumed member given an angular movement thereby by having its extremities in contact with the revolving members, and a train of mechanism connected to the revolving members.

83. In a motor the combination with a casing having three chambers and ports leading from one to the others, of an angularly-movable member operating in one chamber to open and close said ports intermittently and means to intermittently shift the member to open and close positions.

84. The combination with three members in intimate and continual contact, one of which is fixedly fulcrumed and has an angular movement and transmits power to the

- other, and gears for transmitting motion from one to the other.
85. In a motor, the combination with two revolving members and a pivoted and balanced valve having an angular movement in unison with the revolutions.
86. In a motor, the combination with a casing having chambers two revolving and one fixedly fulcrumed and angularly-movable member, said members being in constant contact with each other and projections on the walls of the chambers, and gears for operating the revolving members in unison, and in opposite directions.
87. In a motor, the combination with a pressure-chamber, of a fixedly-fulcrumed member operating in said chamber and without resistance against the pressure, of chambers communicating by ports in the walls of the chambers with said chamber, members rotating in said chambers, and a member being operable to intermittently open and close said ports by the rotation of said members.
88. In a motor, the combination with two revolving irregular-formed members, operating irregularly with respect to their centers, of a fixedly-fulcrumed member given an angular movement thereby, by having its ends in contact with the irregular members, means for maintaining the contact and means for operating the revolving members in opposite directions in similar paths.
89. In a combination of the class specified, a medium-containing chamber, having ports in the walls thereof, for supplying a plurality of contiguously-arranged chambers, of movable parts in said chambers, one of said movable parts being fixedly fulcrumed having an angular movement to intermittently control the medium from the one to the other chambers.
90. A motor-casing, comprising a chamber having three compartments one above two, and communicating through openings and means operating in the openings for cutting off the communication.
91. The combination with a casing comprehending a chamber divided into three compartments in the walls between which are inlet-ports, and two of which chambers have exhaust-ports, a member angularly movable for intermittently opening and closing the inlet-ports, and members operative for automatically operating said member and simultaneously opening and closing the exhaust-ports.
92. The combination with three compartments comprehended within a chamber, and between one and two of which there is an inlet-port, the said two being also provided with exhaust-ports, members operating to automatically open and close the exhausts, and an angular movable member operated by said members for opening and closing the inlet-ports.
93. In a motor, the combination with two revolving disks of irregular form, of a fixedly-fulcrumed member having its ends bearing on said disks, and so actuated thereby as to have its ends carried up and down intermittently, said disks and member being constantly in contact, and means for actuating the disks.
94. In a motor, the combination with a casing having chambers, two rotating and one fixedly fulcrumed and having its ends movable perpendicular and intermittently, said members being in close contact with each other and with projecting walls of the chambers.
95. In a motor, the combination with the casing having chambers one above two, which are located side by side, and ports leading from one to another, of a member having an angular movement in one chamber to open and close said ports, and members having irregular form and operating in constant contact with two points on said member, for causing an intermittent movement of the member.
96. In a motor, the combination with working members, means for operating the same in opposite directions, and an intermediate member driven angularly through independent paths, by having two portions thereof in contact with both working members, and a bearing for said intermediate member.
97. In a motor, the combination with two revolving members, gears for revolving the same in opposite directions and an intermediate working member driven angularly through independent paths, by having two portions thereof in contact with both working members, and a bearing for the intermediate member.
98. The combination with working members, each revolving about dissident axes, and a fixedly-fulcrumed member operated thereby through an angular path.
99. The combination with a casing having three chambers, of an element operable in each chamber, one of said elements being shiftable angularly and effectual to control the flow of a medium from one chamber to the others containing the other elements.
100. The combination with chambers having inlet and exhaust ports, members operating in two of said chambers, and one member operating in another chamber, and under the pressure of a medium directed against one surface thereof, and which automatically opens and closes said ports, said members shielding the other side of the member from medium pressure.
101. The combination with two working members operating about dissident axes, and an integral fixedly-fulcrumed member, which is given an angular movement by the operation of the working members.

102. In a motor the combination with two members moving about independent axes of an angularly-movable member operated thereby about a fixed fulcrum relatively between the rotating members.

103. The combination with three movable members two of which are rotatably mounted about independent axes, of one which operates about an axis fixed intermediate the axis of the rotatably-mounted members and which is operated by said rotatably-mounted members.

104. The combination with fixedly-fulcrumed angularly-movable means, members moving on opposite sides of the fulcrum and adapted to operate the means and a casing for the elements, which is divided into casing-sections one of which is a pressure-chamber, communication from which is governed by the angularly-movable means.

105. In a motor, the combination with three working members two of which revolve, and one of which is integral and fulcrumed at a fixed point between the two members and has an angular movement in coincidence with the revolutions of the members, and means operatively connecting the two members.

106. In a motor, the combination with an

angular-movable member, rotating about a fulcrum fixed relatively to the motor-casing, and a plurality of means to operate the member, said fulcrum being between the axes of the means.

107. The combination with a casing having chambers, of an element rotatable in each chamber, one of said elements having a fixed fulcrum between the axes of the rotatable elements and an angular movement and being effectual for controlling the flow of a medium to the chambers containing a plurality of elements.

108. The combination with fixedly-pivoted angularly-movable members, rotatably-mounted members adapted to operate said members, said pivot between the axes of rotation of the members, and a casing for the elements, which is divided into casing-sections one of which is a pressure-chamber, communication from which is governed by the angularly-movable means.

Signed at Nos. 9 to 15 Murray street, in the city, county, and State of New York, this 6th day of February, 1905.

CHARLES S. BATDORF.
